CLAIM

The ornamental design for a wall mount, as shown and described.

DESCRIPTION

FIG. 1 is a top, front perspective view of a wall mount;

FIG. 2 is a bottom, back perspective view thereof;

FIG. 3 is a front view thereof;

FIG. 4 is a back view thereof;

FIG. 5 is a right-side view thereof;

FIG. 6 is a left-side view thereof;

FIG. 7 is a top view thereof;

FIG. 8 is a bottom view thereof;

FIG. 9 is a bottom, back perspective view showing disclaimed environmental context; and,

FIG. 10 is a left-side view thereof.

The dashed broken lines depict portions of the wall mount or environmental context of the wall mount that form no part of the claimed design.

1 Claim, 10 Drawing Sheets
